UNITED STATES PATENT OFFICE.

BEN K. FORD, OF OAK PARK, AND ERNEST M. HALLBAUER, OF MAYWOOD, ILLINOIS,
ASSIGNORS TO AMERICAN CAN COMPANY, OF NEW YORK, N. Y., A CORPORATION OF
NEW JERSEY.

CAN.

1,318,370.

Specification of Letters Patent. Patented Oct. 14, 1919.

Application filed April 17, 1914. Serial No. 832,406.

To all whom it may concern:

Be it known that we, BEN K. FORD, a citizen of the United States, residing in Oak Park, in the county of Cook and State of Illinois, and ERNEST M. HALLBAUER, a citizen of the United States, residing at Maywood, in the county of Cook and State of Illinois, have invented a new and useful Improvement in Cans, of which the following is a specification.

This invention relates to improvements in cans.

One object of the invention is to provide a can or receptacle which may be easily, quickly and securely sealed at the place where filled and so sealed that the can cannot be opened before reaching the user without leaving visual evidence thereof.

Another object of the invention is to so construct the can top and the seam by which the closure is secured in position that provision is made for the reception of a friction slip fitting cap to protect the closure in transit, the closure being of such material that it may be easily severed by the user.

The invention furthermore consists in the improvements in the parts and devices and in the novel combinations of the parts and devices herein shown, described or claimed.

In the drawing forming a part of this specification Figure 1 is a perspective view of a portion of a can showing one form of our improvements in connection therewith. Fig. 2 is a sectional view showing the top portion of a can embodying our improvements, and Fig. 3 is a similar view but with the cap removed and showing in dotted position the seam-forming flange before the closure is finally secured in place.

In said drawing, the body of the can is designated by the reference 10, said body being shown as made of paper although it may be of any other suitable construction. The can is provided with a sheet metal top 11 secured to the body 10 by a crimped seam 12, said top having a countersunk portion 13 surrounding an opening 14. The top 11 has an upwardly extended flange 15 surrounding and defining the opening, an inwardly

extending bead 16 formed by doubling the 50 metal upon itself as shown in Figs. 2 and 3, and a flange 17 which, before the closure 18 is applied, occupies the position shown in dotted lines at 19. The closure 18, which may be of paper or any other relatively 55 easily severable material, is placed on the shelf or ledge formed by the bead 16 after the can has been filled and then the flange 17 is bent by any suitable means from the dotted position shown at 19 to the position 60 shown in section in Figs. 2 and 3. In this manner the closure 18 is permanently secured in position and a very tight seam is formed. As will be apparent, after the flange 17 is bent or curled inwardly to secure the closure in place, the closure cannot be removed or tampered with without leaving visual evidence thereof, although the user may readily obtain access to the can's contents by severing the closure 18 70 with a knife or other suitable instrument.

In turning the flange 17 down upon the closure, an outwardly extending bead 20 is formed which serves as a friction wall for the flange 21 on the cap or cover 22, the 75 flange 21 being slightly curled inwardly at its lower edge so that as it passes over the bead 20 it will snap into position and be firmly held. The top 11 is countersunk to such an extent that when the cap 22 is in 80 position the top of the latter will be substantially flush with the upper edge of the can body whereby the cans may be easily stacked for shipping purposes.

Although we have herein shown and described what we now consider the preferred embodiment of our improvements, yet it will be understood that various changes and modifications may be made without departing from the spirit of the invention, and all 85 such changes and modifications are contemplated as come within the scope of the claim appended hereto.

We claim:

A can formed with an aperture, said aperture being surrounded by an outstanding flange, said flange being bent inward and thence outward to form a seat and being 95

thence bent upward to form an external peripheral shoulder for holding a friction top, and thence bent inward to form a securing flange; a closure on said seat held beneath said securing flange; and a friction top having a depending friction flange adapted to engage around and under said external peripheral shoulder.

Signed this 11th day of April, 1914, in the presence of two witnesses.

BEN K. FORD.
ERNEST M. HALLBAUER.
